UNITED STATES PATENT OFFICE.

LAZARD KAHN, OF HAMILTON, OHIO, ASSIGNOR TO F. & L. KAHN & BROS.,
OF SAME PLACE.

DESIGN FOR A GAS-STOVE.

SPECIFICATION forming part of Design No. 32,801, dated June 5, 1900.

Application filed May 7, 1900. Serial No. 15,840. Term of patent 14 years.

To all whom it may concern.

Be it known that I, LAZARD KAHN, a citizen of the United States, residing at Hamilton, Butler county, Ohio, (post-office address, Hamilton, Ohio,) have invented and produced a new and original Design for Gas-Stoves, (Case H,) of which the following is a specification, reference being had to the accompanying drawing, forming part thereof, which drawing is a front perspective view of a gas-stove, showing my new design.

As shown in the drawing, the front of the stove is rectangular in form, its design being characterized by side pilasters A, terminating below in volute-shaped feet B, the pilasters being enriched by molded and fluted band C, disposed over the feet and also about midway of the length of the pilasters, the pilasters being further enriched by helically-arranged fillets. Across between the bases of the pilasters extends a skirting D, whose

lower margin has a downwardly-presenting convex outline ornamented by beading, the face of the skirting being enriched by a pair of intermembrancing sinusoidal lines of carving. In the upper and lower portions, respectively, of the space between the pilasters, above the skirting, are disposed the rectangular doors or panels E and F, margined at their tops and bottoms and sides by the 25 carved enrichments G, consisting of series of 30 semicircular foliate ornaments.

Having described my invention, what I claim as new, and desire to secure by Letters Patent, is—

The design for a gas-stove, as herein shown and described.

LAZARD KAHN.
